UNITED STATES PATENT OFFICE.

EDWARD BRUNHOFF, OF CINCINNATI, OHIO.

DISPLAY AND VENDING APPARATUS.

Application filed April 30, 1925. Serial No. 27,030.

My invention relates to improvements in display and vending apparatus. One of its objects is to provide a support and a lid hinged thereto adapted to be employed in connection with either original sheet metal, 5 vitrified, or similar containers to display and vend the contents of said containers. Another object is to provide improved display and vending apparatus adapted to protect 10 counters and show cases, upon which the original containers are to be supported, against injury and breakage due either to placing the original containers directly upon or carelessly upon the counter or show case, 15 or from dropping or resting the lids of the containers directly upon the counters or show cases. Another object is to provide improved means to support the original containers upon and relative to show cases with- 20 out liability to injure or break the counter or show case. Another object is to provide improved means to hinge and support a lid upon and relative to the original container, either the original lid, or another lid, pref- 25 erably having a transparent section to display the contents of the original container. My invention also comprises certain details 30 of form, and combination and arrangement of components, all of which will be fully set forth in the description of the accompanying drawings, in which:

Fig. 1 is a central vertical section through a display and vending apparatus embodying my invention, being a section on line 1—1 35 of Fig. 2.

Fig. 2 is a plan of the apparatus shown in Fig. 1.

Fig. 3 is a perspective view of one of the lid supporting members detached.

Fig. 4 is a perspective detail of one of the lid hinge members detached.

Fig. 5 is an enlarged sectional detail taken on line 5—5 of Fig. 2.

The accompanying drawings represent the preferred embodiment of my invention in which 15 represents a base member, constructed for instance of wood or similar material having a depression 16 or similar means to receive and retain an original container 17 in position upon and relative to said base member. As illustrated the original container 17 consists of a transparent glass jar, in which for instance cigars, tobacco, or other goods to be vended, are packed, shipped, and put on display to be vended. The container 17 may be cylin-

drical, rectangular or of other design. Sheet metal original containers 17 externally covered with labels or trade-marks are also designed to be employed in place of the 60 transparent glass containers. During shipment the original containers 17 may be closed by means of a sheet metal lid, or if desired by means of a transparent lid 19, such as shown in Figs. 1 and 2 for instance. 65 When it is desired to place the contents of an original package on display for sale, the sheet metal or other lid with which the original package was shipped is removed and the original package 17 mounted in 70 position upon the base member 15. A pair of hinge rods 20 and 21 are mounted vertically in recesses in the base member and their upper ends 22 are turned at substantially right angles to said rods, and away 75 from each other.

The lid 19 which may be of molded glass, a disk of plate or sheet glass, or if desired of other material, is embraced by a split metal band 24 having hinge members or 80 brackets 25 and 26 attached to opposite ends thereof. A clamping screw 27 serves to clamp the two projections 30 and 31, attached to opposite ends of the band 24, together to hold the band detachably in place 85 upon the lid 19. The band 24 is provided with a series of projections 28 extending inwardly above and below the edge of the lid 19 to hold the band in place relative to the lid. A projection 29 at the front of the 90 band 24 assists in lifting the lid from the container 17 when required. The hinge brackets 25 and 26 are perforated at 32 to receive the outwardly turned ends 22 of the rods 20. The hinge brackets also have 95 ledges 33 vertically above the vertical sections of the rods 20 which serve to stiffen the hinge brackets, to prevent displacement of the hinge brackets relative to the rods 20 and members 22, and to limit the hinge 100 movement of the lid upon and relative to the members 20 and 22, so that the lid may not be tilted sufficiently to the rear of the rods 20 to upset the base member 15. The lid 19 is preferably provided with an annular 105 recess 34 in which is mounted an annular band 35 of rubber, cork, or similar resilient material, which is interposed between the lid and the upper annular rim of the original container. The inclined face 37 of the base member is designed to be employed for advertising purposes. The under face of the 110

base member 15 is preferably armed with sections 39 of rubber, cork, wool-felt or similar resilient material adapted to prevent injury to a counter or show-case due to setting the base-member 15 thereon, or moving it about thereon. The rods 20 and 21 are sufficiently resilient to enable their upper ends to be sprung together when the hinge members are to be engaged therewith.

As heretofore employed the original containers when set directly upon the counters or show-cases or moved about thereon, caused considerable damage, particularly breakage of the glass of the show-cases.

Also the counters and show cases were frequently injured and the glass broken, due to lifting the lid from the container and accidentally dropping the lid upon the counter or show-case. All of these sources of injury to

the counter or show-case are obviated, as the lid is hinged to the base member so as not to contact with the show-case or counter and the original container is mounted upon the base member, which is arranged to rest upon

the counter or show-case without injury thereto. Also the lid is guided centrally to its seat upon the rim of the container so as not to injure either lid or container even though the lid be allowed to fall to position upon the container.

The apparatus herein shown and described is capable of considerable modification within the scope of the claims without departing from the spirit of my invention.

What I claim is:

1. In combination with a display and vending apparatus having a base member adapted to be seated upon a show-case and provided upon its upper face with means to engage and hold an original container in a predetermined position relative to said base and an original container mounted in position on said base, a pair of resilient hinge rods projecting upwardly from said base to the upper portion of said original container, said hinge rods having their upper free ends turned away from each other and at substantially right angles to the vertical position of said rods, and a lid having hinged relation to the upper ends of said hinge rods with a limited hinge movement and guided by said hinge rods from an open position to a position to close the open mouth of said original container, said hinge rods being adapted to have their upper free ends sprung toward each other and out of their normal position to be operatively engaged in hinged relation with or disengaged from said lid.

2. A display and vending apparatus comprising a base-member adapted to be seated upon a show-case and provided upon its upper face with means to engage and hold an original container in a predetermined position relative to said base, a pair of hinge

rods projecting upwardly from said base to the upper portion of an original container mounted upon said base-member said hinge rods having their free ends turned at substantially right angles to the vertical portions of said rods and adapted to have their upper free ends sprung out of their normal position to be operatively engaged in hinged relation with or disengaged from the lid, a lid of transparent material, a band encircling said lid and having its ends clamped together to retain said band in position upon the lid, and a pair of hinge members rigidly attached to said band and hinged upon the turned upper ends of said hinge rods, and projections carried by said hinge members to engage the vertical sections of said hinge rods, to limit the hinge movement of said lid relative to said hinge rods.

3. A display and vending apparatus comprising a base-member adapted to be seated upon a show-case and provided upon its upper face with means to engage and hold an original container in a predetermined position relative to said base, a pair of hinge members projecting upwardly from said base-member to the upper portion of an original container mounted upon said base-member, said hinge members having their free ends turned at substantially right angles to the vertical portions of said hinge members and adapted to have their upper free ends sprung out of their normal position to be operatively engaged in hinged relation with or disengaged from the lid, a lid, a band encircling the lid and having its ends clamped together to retain said band in position upon said lid, and a pair of hinge members of angular cross-section rigidly attached to said band and perforated through the vertically disposed sections of said angle to hinge upon the turned upper ends of the base supported hinge members with the ends of the horizontally disposed sections of said angles in position to engage the vertical sections of said base supported hinge members to act as stops and limit the hinge movement of said lid relative to said base.

4. A display and vending apparatus comprising a base-member adapted to be seated upon a show-case and provided upon its upper face with means to engage and hold an original container in a predetermined position relative to said base, a pair of resilient hinge rods spaced apart and projecting upwardly from said base to the upper portion of an original container mounted upon said base member, said hinge rods having their upper free ends turned at substantially right angles to the vertical portions of said rods and adapted to have their upper free ends sprung out of their normal position to be operatively engaged in hinged relation with or disengaged from the lid, a lid hav-

ing a section of resilient material to engage the rim of an original container, a band encircling the lid and having its ends clamped together to retain said band in position upon said lid, and a pair of hinge members attached to said band and perforated to engage the turned free ends of said hinge rods

in hinged relation, said hinge members being provided with stops to limit the hinge movement of said lid relative to said base. ¹⁰

In testimony whereof, I have affixed my signature.

EDWARD BRUNHOFF.
